AUDIPHONE

Arthur S. Craig, Kansas City, Mo., assignor to
 Western Electric Company, Incorporated,
 New York, N. Y., a corporation of New York

Application May 22, 1934, Serial No. 726,912

4 Claims. (Cl. 179—107)

This invention relates to hearing aids for the deaf and more particularly to supporting means for such devices.

The object of the invention is to provide a supporting means for devices of this type which will be inconspicuous when in use, easily adjustable to the head of the user and comfortable to wear.

In accordance with the general features of this invention, the supporting means comprises a supporting band of resilient material adapted to span the back of the head from ear to ear and lie below or closely adjacent to the hair line at the back of the head and to be additionally supported by engagement with the upper portions of the ears.

As a further feature of this invention the supporting band may be provided and equipped with means for supporting a bone conduction receiver in operative relation to the mastoid eminence of the head.

According to this feature of the invention there is provided upon the band means adjacent one or both ear portions a loop member or extension adapted to receive a supporting member preferably of resilient material for adjustably supporting a bone conduction receiver.

In the drawing illustrating this invention,

Fig. 1 is a profile view of a human head showing the application of the invention thereto;

Fig. 2 is a view in perspective of the apparatus of this invention in assembly; and

Fig. 3 is a view in side elevation of the receiver and a portion of gear.

As shown in the drawing, particularly Fig. 2, the receiver support comprises a pair of frame members 5 and 6 which may be formed of resilient wire. The two members 5 and 6 are provided at their inner ends with flattened portions 7 and 8, respectively. The portion 7 carries a slide member 9 adapted to receive the portion 8 and the portion 8 carries a slide 10 adapted to receive the portion 7. The slide portions 9 and 10 are secured to the ends of the respective portions 7 and 8 so that the members 5 and 6 may be adjustable as to length.

At their free ends the members 5 and 6 are provided with hook portions 11 and 12, respectively, which are adapted to hook over the top portions of the ears of the user as illustrated in Fig. 1. Due to the resilient nature of the material of the band and the fact that it is easily adjustable as to length, the device may be made to fit snugly around the back of the head without exerting an uncomfortable backward pull upon the ears

through the hook portions 11 and 12 and without placing excessive pressure upon any localized portion of the head to the discomfort of the user. The hook portions 11 and 12 may be protected by suitable material well known to oculists for preventing direct contact of the metal with sensitive portions of the user.

In the members 5 and 6 there are provided loops 14 and 15, respectively, which when the support is in use will be in close proximity to the mastoid eminence. These loops 14 and 15 are for the purpose of supporting a bone conduction receiver 16 in operative relation to the mastoid eminence.

The supporting mechanism for the receiver 16 is formed of light resilient metal and in form comprises an upper hooked portion 17 curved longitudinally to engage and slide upon the loop portion 14, a flat portion 18 adapted to lie between the member 5 and the head of the user, a horizontally extending portion 19 and an enlarged portion 20 for adjustably supporting the receiver 16. The adjustable supporting feature is provided by means of two oppositely disposed arcuate slots 21 and 22 through which extend set screws 23 and 24 which engage the receiver 16.

The allowable movement of the receiver supporting member upon the loop portion 14 in combination with the movement of the receiver upon its support and the adjustability of the members 5 and 6 permits such a latitude of adjustment that the receiver can be adjusted readily to the most sensitive vibration responsive portion of the mastoid eminence of practically any individual thus eliminating the necessity of making to measure a supporting equipment for the individual patient.

By reason of the resilience of the members 5 and 6 and of the receiver supporting member which, in addition to its own resilience, receives pressure from the member 5, sufficient pressure can be exerted between the receiver and the head of the user to insure an efficient acoustic coupling by quite light weight materials, thus reducing to a minimum the weight and pressure upon the head of the user.

What is claimed is:

1. The combination with a bone conduction receiver of a resilient supporting band adapted to encircle the back of the head, the band being provided at its ends with hooks adapted to engage over the tops of the ears and adjacent one end portion with a loop, and a receiver supporting member adjustably supported upon the loop.
2. The combination with a bone conduction re-

- ceiver of a resilient supporting band adapted to encircle the back of the head, the band being provided at its ends with hooks adapted to engage the tops of the ears and adjacent one end with a loop, a receiver supporting member adjustably carried by the loop, and a bone conduction receiver adjustably secured to the supporting member.
3. The combination with a bone conduction receiver of a resilient and adjustable band adapted to encircle the back of the head, the band being provided at its ends with hooks adapted to engage over the tops of the ears and adjacent one end with a loop, a receiver, and a receiver

support engaged by the looped portion of the band to press the receiver against the mastoid eminence of the user.

4. In an audiphone apparatus in combination, a resilient and adjustable band adapted to encircle the head of the user, the band being provided with hooks adapted to engage the tops of the ears, and with a loop portion, a receiver holder supported by the loop portion and angularly adjustable thereon, and a bone conduction receiver carried by the receiver holder and angularly adjustable thereon.

ARTHUR S. CRAIG.
